TOY BOMBING GAME

Henry M. Hanna, Kansas City, Mo., assignor of
one-fourth to Verne H. Nye, Kansas City, Mo.

Application September 29, 1943, Serial No. 504,278

6 Claims. (Cl. 273—95)

This invention relates to amusement devices in the nature of a toy or game having means for throwing a projectile through space toward a target, which is preferably horizontally disposed, and the primary aim is the provision of such a toy wherein is included simple, rugged, yet efficient means for shiftably maintaining a projecting beam in proper relation with sighting mechanism whereby the projectile may be cast upon the target with accuracy.

Another object of this invention is the provision of a toy bombing or projectile casting apparatus characterized by unique and specially combined sighting and propelling mechanism, which takes into account the trajectory of the propelled article, to the end that the target is struck thereby when said target is in alignment with the sighting element of the apparatus.

A further aim of this invention is to provide a toy of the aforementioned character, having a head shiftable about a vertical axis and a pair of beams or the like, swingable about horizontal axes, which beams are held in proper angular relation depending upon weight of the projected article, strength of the projecting force, and distance to the target forming a part of the game.

A large number of minor objects including the specific manner of embodying the invention in one form of apparatus, will appear during the course of the following specification, referring to the accompanying drawing wherein:

Fig. 1 is a side elevational view of the toy bombing game made to embody the present invention.

Fig. 2 is an enlarged fragmentary sectional view through the upper portion of the projecting apparatus of the game, parts being left in elevation for clearance of disclosure.

Fig. 3 is a horizontal sectional view through the game taken on line III—III of Fig. 2, looking in the direction of the arrow.

Fig. 4 is an enlarged fragmentary cross sectional view through the projecting beam taken on line IV—IV of Fig. 2.

Fig. 5 is an elevational view of one end of projecting beam illustrating one way of constructing a trigger mechanism for the game; and

Fig. 6 is an elevational view of one end of the sighting beam, showing the cross hairs thereof.

The game comprises a target 10 preferably disposed horizontally and having thereon such pictorial illustrations as may simulate a map, battle field, or the like, a standard 12 and a head generally designated by the numeral 14.

Head 14 is pivotally mounted upon standard 12 by a pin or analogous means 16, disposed on a vertical axis to permit free movement of head 14 when the game is in use.

Head 14 comprises one or more uprights 18 mounted on standard 12 through the medium of a block or the like 20. Upon these uprights is disposed a pair of beams 22 and 24. Beam 22 is carried by a horizontal pivot point 26 while beam 24 is likewise secured to uprights 18 by a similarly disposed pivotal pintle 28.

Beams 22 and 24 are maintained at different angles of inclination with respect to the horizontal and the normally forward ends of beams 22 and 24 are maintained closer together than the rear ends thereof. A link 30 pivotally secured as at 32 and 34 to beams 22 and 24 respectively, maintains the relation between these beams and as one of said beams is shifted about its vertical pivotal point, the other beam follows.

Beam 22 has a track 36 formed along the forward portion of its upper edge to receive the projected member 38 which should be in the nature of a dart or the like, having a point 40 capable of penetrating a part of target 10. A bearing block 42 on beam 22 journals plunger 44 for rectilinear reciprocation and a head 46 on the end of plunger 44, which directly engages member 38, limits the movement of plunger 44 in one direction. A trigger 48 limits the movement of plunger 44 in the opposite direction.

Spring 50 having one of its ends attached to trigger 48 is anchored at its other end to one of a number of pins 52 carried by beam 22 and when trigger 48 is moved from behind stop 54, spring 50 will draw plunger 44 to the forward end of its path of travel—thus, member 38 is projected with a snapping action along track 36 and thence to target 10 in the trajectory path, shown by the dotted lines in Fig. 1. The force of spring 50, weight of member 38, and angularity of beam 22 with respect to target 10, is such as to cause member 38 to engage the target when the target is on a straight line projected outwardly from sighting beam 24.

This line of sight is indicated by the dot-and-dash line of Fig. 1.

Beam 24 has a central longitudinal bore 55 therethrough and a peep hole 56 at one end. Cross hairs 58 at the opposite end of beam 24 completes the inclusion in beam 24 of the necessary elements to accurately sight the apparatus prior to releasing trigger 48 to project member 38 toward target 10.

The tension of spring 50 may be increased or

decreased to suit conditions by moving one end thereof into engagement with the appropriate pin 52 and in the event it is desired to vary the regular angularity between beams 22 and 24, pin 32 may be moved to another socket 60 formed in beam 22.

Obviously from the foregoing, it will be observed that the apparatus may be adjusted to properly project a movable member onto the target, regardless of the distance of the target from the elevated sight and projecting beam, and that if it is desired to vary the distance of the target from the projecting apparatus, the force of spring 50 may be altered accordingly as may the degree of angularity between beams 22 and 24.

Link 30 in the illustrated embodiment of the invention, maintains the forward ends of beams 22 and 24 closer together than the other ends thereof, and the movement of one beam, which is transmitted to the other, will progressively change the distance between these said forward ends. The angularity of the track 36 is changed so that the ends of beams 22 and 24 approach each other as beam 24 nears the horizontal position. As target 10 is moved from the projecting head, the angle of sight approaches the horizontal and the angle of projection is elevated to change the trajectory path to assure a striking of the target.

Since the invention may be embodied in toy bombing games having physical characteristics different from those illustrated, and further since the particular form of the parts entering into the combination producing the apparatus may be varied to a considerable degree, it is desired to be limited only by the spirit of the invention and scope of the appended claims.

Having thus described the invention, what is claimed as new and desired to be secured by Letters Patent is:

1. A game device of the character described, comprising a standard movable about a vertical axis; a pair of beams mounted one above the other, on said standard for movement about separate horizontal, parallel axes; sighting structure on one of the beams to establish a line of sight; mechanism for projecting a free member from the other beam; and means for maintaining the beams at different angles to the horizontal as the same are shifted about their axes whereby said line of sight and the trajectory of the free member converge at a selected point.

2. A game device of the character described, comprising a standard movable about a vertical axis; a pair of beams mounted, one above the other, on said standard for movement about separate horizontal, parallel axes; sighting structure on one of the beams to establish a line of sight; mechanism for projecting a free member from the other beam; and means interconnecting the pair of beams for causing the same to move simultaneously about their axes and for holding the beams at different angles to the horizontal

whereby said line of sight and the trajectory of the free member converge at a selected point.

3. A game device of the character described, comprising a standard movable about a vertical axis; a pair of beams mounted, one above the other, on said standard for movement about separate horizontal, parallel axes; sighting structure on one of the beams to establish a line of sight; mechanism for projecting a free member from the other beam; and means interconnecting the pair of beams for causing the same to move simultaneously about their axes and for holding the beams at different angles to the horizontal whereby said line of sight and the trajectory of the free member converge at a selected point, said beams having their angularity with respect to each other, progressively changed as the same are moved about their horizontal axes.

4. A game device of the character described comprising a standard movable about a vertical axis; a pair of beams mounted, one above the other, on said standard for movement about separate horizontal, parallel axes; sighting structure on one of the beams to establish a line of sight; mechanism for projecting a free member from the other beam; means for maintaining the beams at different angles to each other as the same are shifted about their axes; and a guide for the free member on the said other beam.

5. A game device of the character described comprising a standard movable about a vertical axis; a sighting member on the standard movable about a horizontal axis to establish a line of sight; a projectile track shiftably carried by the standard; means on the projectile track for directing a freely movable missile along the track; and linkage joining the sighting member and the said track for progressively changing the angle of said track with respect to the horizontal and the trajectory of the freely movable missile as the sighting member is moved about its axis whereby said line of sight and the trajectory of the free missile converge at a selected point.

6. A game device of the character described comprising a standard movable about a vertical axis; a sighting member on the standard movable about a horizontal axis to establish a line of sight; a projectile track shiftably carried by the standard; means on the projectile track for directing a freely movable missile along the track; and linkage joining the sighting member and the said track for progressively changing the angle of said track with respect to the horizontal and the trajectory of the freely movable missile as the sighting member is moved about its axis, said freely movable member being provided with radial fins at one end thereof, said track being formed to present two parallel, spaced apart contact edges and a longitudinal groove therebetween for receiving one of the said fins.
